UNITED STATES PATENT OFFICE.

CHARLES W. WYMAN, OF CLAREMONT, NEW HAMPSHIRE, ASSIGNOR TO SULLIVAN MACHINERY COMPANY, A CORPORATION OF MASSACHUSETTS.

MINING APPARATUS.

Application filed July 25, 1919, Serial No. 313,206. Renewed October 16, 1923.

To all whom it may concern:

Be it known that I, CHARLES W. WYMAN, a citizen of the United States, residing at Claremont, in the county of Sullivan and State of New Hampshire, have invented certain new and useful Improvements in Mining Apparatus, of which the following is a full, clear, and exact specification.

My invention relates to mining apparatus.

10 It has for its object to provide an improved and simplified controlling mechanism for electrically propelled mining machines. A further object of my invention is to provide an improved controlling mechanism for such machines wherein sparking at the controller is eliminated, the danger of grounding on the machine frame is minimized, and wherein without unduly increasing the cost of the apparatus the entire mechanism may be made to function in an improved manner. These and other objects and advantages of my improved construction will, however, hereinafter more fully appear.

25 For purposes of illustration, I have shown in the accompanying drawings one embodiment which my invention may assume in practice.

In these drawings,—

30 Fig. 1 is a plan view of a mining apparatus equipped with my improvement.

Fig. 2 is a diagram of the circuit connections.

35 In this illustrative construction I have shown a mining machine 1 which may be of any desired construction adapted to be transported upon a usual mining machine truck 2, the mining machine having an electric motor 3 connected to a cable 4 on a cable reel 5 carried on the truck, through connections including an intermediate flexible lead or cable 6, all in a generally well known manner.

45 In this construction the controller mechanism, illustrated generally in Fig. 1 at 7, and including a supplemental controlling switch, hereinafter described, is shown to be enclosed in one side of the mining machine, and the resistance controlled thereby, herein indicated at 8, is also carried by the machine and herein enclosed in the opposite side of the same, while an improved controlling switch, hereinafter described, controlled by the controller and itself controlling the main motor circuit, is, with the

usual line fuses 22, disposed in the line, the same herein being disposed between the lead 6 and suitable reel leads 9 and 10 connected to the opposite ends of the reel 5, both the contactor and the fuses preferably being housed in a suitable casing 11 disposed on the truck slightly in front of the reel and connected between the lead 6 and the reel leads 9 and 10.

Referring to Fig. 2, it will be observed that I have shown in this figure a wiring diagram of the electrical connections required, substantially as described and claimed in my co-pending application Serial No. 300,455, filed May 28, 1919. As the controller mechanism and these electrical connections, however, do not enter specifically into the present invention, it is believed unnecessary to consider the same more in detail herein than to say that when the controller member, herein an arm 12, is operated to cut out or in the resistance 8 connected in the armature circuit, gripping contacts 13 movable with the arm engage a slideable sector 14 and, through the interlocking of this sector with a bell crank switch member 15, cause the latter to be thrown into or out of engagement with a contact 16, thereby opening or closing a light control circuit through a conductor 17 connected to the line conductors 18, 19, and adapted to energize or deenergize an electro-responsive switch or contactor 20 to close or open one side of the line, herein making or breaking the current flow through contacts 21 in the line conductor 18. Herein, it will be observed that the entire controller, including its resistance and its switch 15, is carried upon the machine frame 1, and that the contactor 20 is disposed between the motor and the line, the same herein being carried upon the rear end of the truck frame and preferably housed in the same casing 11 with the line fuses 22.

As a result of my improvement wherein 100 a supplemental line circuit making and breaking mechanism is used and the controller per se serves only to make or break a controlling circuit for a contactor which takes all the arcing, objectionable arcing 105 on the machine is eliminated and the danger of grounding on the machine frame, and consequent danger to the operator, is minimized. At the same time it will be noted that a simple and inexpensive construction 110

is made possible, and one which, if desired, permits the contactor to be carried on the truck by the use of only a single additional conductor in the cable 6. Further, it will be observed that by locating my improved contactor on the truck, as distinguished from on the machine, the space available on the machine is materially increased so that the size of the mining machine mechanism per se, which is preferably housed within in the machine casing, is not limited by the necessity for reserving space for the controlling mechanism. Attention is also directed to the fact that through mounting the contactor upon the truck, as distinguished from upon the machine, the injurious vibration to which the contactor would otherwise be subjected is eliminated, the machine being removed from the truck during cutting so that the contactor is subject to no vibration whatsoever.

While I have in this application specifically described one embodiment which my invention may assume in practice, it will be understood that this form of the same is used for purposes of illustration, and that the invention may be modified and embodied in various other forms without departing from its spirit or the scope of the same as claimed.

What I claim as new and desire to secure by Letters Patent is:

1. The combination with a mining machine, of an electric motor on said machine, electric controlling mechanism on said machine including a movable controller member, resistance means controlled by said controller member, a line circuit making and breaking mechanism controlling current supply to said motor and disposed between the latter and the line, a control circuit for said line circuit making and breaking mechanism, and a switch on said machine controlling the flow through said control circuit and controlled by said controller member.

2. The combination with a mining machine, of an electric motor on said machine, electric controlling mechanism on said machine including a movable controller member, resistance means controlled by said controller member, a line circuit making and breaking mechanism controlling current supply to said motor and disposed at a point removed from said machine, a control circuit for said line circuit making and breaking mechanism, and a switch on said machine controlling the flow through said control circuit and controlled by said controller member.

3. The combination with a mining machine, of an electric motor on said machine, electric controlling mechanism on said machine including a movable controller member, resistance means controlled by said con-

troller member and carried therewith on the machine, a line circuit making and breaking mechanism controlling current supply to said motor and disposed at a point removed from said machine, a control circuit for said line circuit making and breaking mechanism, and a switch on said machine controlling the flow through said control circuit and controlled by said controller member.

4. The combination with a mining machine, of an electric motor on said machine, electric controlling mechanism on said machine including a movable controller member and resistance controlled thereby and carried therewith on said machine, a line circuit making and breaking mechanism controlling current flow through said motor and disposed between the latter and the line, a control circuit including a conductor adapted to energize said circuit making and breaking mechanism, and a supplemental switch on said machine controlling the flow through said control circuit and controlled by movement of said controller member.

5. The combination with a mining machine truck, of a mining machine thereon, a cable reel on said truck, an electric motor on said machine, electric controlling mechanism on said machine including a movable controller member and resistance controlled thereby and carried therewith on said machine, a flexible electrical connection between said controlling mechanism and said reel, and a main line circuit making and breaking mechanism between said reel and motor controlling current flow through said connection and controlled by movement of said controller member.

6. The combination with a mining machine truck, of a mining machine thereon, a cable reel transportable with said truck, an electric motor on the machine, electric controlling mechanism on said machine including a movable controller member, resistance controlled thereby, flexible electrical connections between said motor, said controlling mechanism and said reel, and a main line circuit making and breaking mechanism on said truck controlling current flow through said connection and having control means controlled by, but independent of, said controller member.

7. The combination with a mining machine truck, of a mining machine thereon, a cable reel transportable with said truck, an electric motor on the machine, electric controlling mechanism on said machine including a movable controller member and resistance controlled thereby and carried therewith on said machine, a flexible electrical connection between said controlling mechanism and said reel, a main line circuit making and breaking mechanism between said reel and motor controlling cur-

rent flow through said connection, and controlling means therefor on said machine.

8. The combination with a mining machine truck, of a mining machine thereon, 5 a cable reel on said truck, an electric motor on said machine, electric controlling mechanism on said machine including a movable controller member and resistance controlled thereby and carried therewith on said machine, a flexible electrical connection between said controlling mechanism and said reel, and a main line circuit making and breaking mechanism on said truck controlling current flow through said connection 10 and controlled by movement of said controller member.

9. The combination with a mining machine truck, of a mining machine transportable thereon and separable therefrom during 20 cutting, a cable reel on said truck, an electric motor on said machine, electric controlling mechanism on said machine including a movable controller member and resistance controlled thereby and carried therewith 25 on said machine, a flexible electrical connection between said controlling mechanism and said reel, and a main line circuit making and breaking mechanism on said truck controlling current flow through said connection 30 and controlled by movement of said controller member.

10. The combination with a mining machine truck, of a mining machine thereon, a cable reel on said truck, an electric motor 35 on said machine, electric controlling mechanism on said machine including a movable controller member and resistance controlled thereby and carried therewith on said machine, a flexible electrical connection between said controlling mechanism and said reel, a main line circuit making and breaking mechanism on said truck, a control circuit including a conductor in said flexible connection adapted to energize said circuit making and breaking mechanism, and 40

a supplemental switch on said machine controlling the flow through said control circuit and controlled by movement of said controller member.

11. The combination with a mining machine truck, of a mining machine transportable thereon and separable therefrom during cutting, a cable reel on said truck, an electric motor on said machine, electric controlling mechanism on said machine including a movable controller member and resistance controlled thereby and carried therewith on said machine, a flexible electrical connection between said controlling mechanism and said reel, a main line circuit making and breaking mechanism on said truck, a control circuit including a conductor in said flexible connection adapted to energize said circuit making and breaking mechanism, and a supplemental switch on said machine controlling the flow through said control circuit and controlled by movement of said controller member. 50 55 60 65

12. The combination with a mining machine truck, of a mining machine associated therewith, a cable reel transportable with said truck, an electric motor on the machine, a resistance, a member carried by the machine and controlling the resistance in 70 circuit with said motor, flexible motor leads between said controlling means and said reel, connections between said controlling means and said motor, and a main line switch between said means and said reel, said controlling means comprising means cooperating with said main line switch and having a single connection in addition to said motor leads for causing opening of said main line switch prior to the cutting out of resistance 75 80 85 in the motor circuit.

In testimony whereof I affix my signature.

CHARLES W. WYMAN.
